UNITED STATES PATENT OFFICE.

MAX OTTO CLAUSS, OF NEW YORK, N. Y., ASSIGNOR TO THE CLARK THREAD COMPANY, OF NEWARK, NEW JERSEY, A CORPORATION OF NEW JERSEY.

SKEIN-WINDING MECHANISM.

1,401,516.

Specification of Letters Patent. Patented Dec. 27, 1921.

Application filed September 18, 1919. Serial No. 324,530.

To all whom it may concern:

Be it known that I, MAX OTTO CLAUSS, a citizen of Germany, and a resident of New York, in the county of New York and State 5 of New York, have invented certain new and useful Improvements in Skein-Winding Mechanism, do hereby declare that the following is a full, clear, and exact description of the same.

10 This invention relates to an improved skein winding mechanism and has for its primary object to provide a relatively simple mechanism for rapidly winding the yarn, cotton, silk or other thread into skeins 15 in the manner shown in my pending application for patent filed August 1st, 1919, Serial Number 314647.

Generically considered, the present invention comprehends the provision of means 20 for imparting to a flier arm or thread carrier a composite movement in two directions to thereby wind the thread in the desired manner around the spaced parts of a skein holder.

25 More specifically, the invention consists in the provision of a shaft mounted for axial and rocking or rotary movement, the said shaft having a flier fixed to one of its ends to operate in conjunction with the skein 30 holder of the form shown in my said application. For the operation of this shaft in a positive manner I provide a pair of cams and means operatively connected to the shaft and actuated by one of such cams for transmitting an axial movement to the shaft, and 35 additional means also operatively connected to the shaft and actuated by the other cam for imparting a rocking or rotary movement to the shaft.

40 I further contemplate the provision of a skein winding mechanism as above characterized, the several parts of which are of simple form, not liable to get out of order and which will operate in a highly efficient 45 and reliable manner.

With the above and other objects in view, my invention resides in an improved skein winding mechanism as above characterized and in the form, construction and relative arrangement of its several parts as will be hereinafter more fully described, illustrated in the accompanying drawings and subsequently incorporated in the subjoined claims.

In the drawings, wherein I have disclosed 55 the preferred embodiment of my invention and in which similar reference characters designate corresponding parts throughout the several views.

Figure 1 is a side elevation of a skein 60 winding mechanism showing the relative position of the parts at the starting of the winding operation;

Fig. 2 is a top plan view partly in section; 65

Fig. 3 is an elevation looking at right angles to Fig. 1;

Fig. 4 is a diagrammatic view of the operating cams;

Fig. 5 is a similar view illustrating the 70 movements of the thread carrying flier during one cycle in the winding operation.

Referring in detail to the drawings, 5 designates a suitable frame or bedplate having an upright or standard 6 on one of its ends 75 in the upper end of which one end of a shaft 7 is journaled. Upon this shaft the spaced sprockets 8 are securely fixed, said sprockets being carried by a spacing collar 9 which is securely held upon the shaft 7 against longitudinal or rotary movement with respect thereto.

The sprockets 8 transmit movement to the vertically disposed endless link chains 10. Upon the corresponding alternate links of 85 these chains the skein holders herein generally designated by the numeral 11 are securely fixed. These skein holders comprise no part of the present invention, as such holder forms the subject matter of my co-pending application for patent, Serial No. 346,837, filed December 23, 1919, to which reference may be had for a detail description thereof. For the purposes of the present description it will suffice to state that 95 this holder includes a body member 12 and a relatively movable member 13 which is pivoted upon the body member as at 14. The body member 12 is provided with bifurcated arms 14' projecting from one side of 100 the chains 10 while the movable member 13 is provided with a single relatively long arm 15 projecting from the relatively opposite side of the chains and also bifurcated at its extremity. The member 13 is held in its 105 thread receiving position with respect to the member 12 by means of a suitable latch 16. This member is also provided adjacent pivot

14 with an angularly disposed arm 17 with which a trip element is adapted to engage.

Upon the frame or bedplate 5 a horizontal shaft 18 is mounted in the spaced bearings 19 for axial and rotary movements. To the end of this shaft which is adjacent the standard or upright 6 a flier 20 is securely fixed at its lower end. The upper end of this flier is curved inwardly over the sprocket chains which carry the skein holders and said flier is provided with the usual guide eyes for the yarn or thread.

The bedplate 5 is provided with a depending arm 21 having a bearing sleeve 22 at its lower end in which the shaft 23 is journaled. Upon this shaft at each side of the bearing 22 a cam disk is securely fixed. These cam disks are designated 24 and 25 respectively. A cam rail 26, 27 is associated with each of these disks and conforms to the peripheral shape or contour thereof. The rails are disposed in spaced relation to the edges of the cam disks and are securely held in the plane of said disks by means of the lugs or fingers 28 and 29 respectively which extend inwardly from the rails and are welded or otherwise securely fixed to the respective cam disks. Thus, there is provided between each rail and the edge of the cam disk a cam track 30 and 31 respectively.

Upon the depending part or bracket 32 of the frame or bedplate 5 a lever 33 is fulcrumed intermediate of its ends as at 34. The upper end of this lever which extends above the bedplate 5 is pivotally connected as at 35 between the ends of a sectional link 36. The other ends of the linked sections are formed with the mating halves of a socket 37 to receive the spherical terminal 40 or ball 38 on a rod 39 which is fixed in the end of the shaft 18 by means of the set screw 40. Thus, it will be evident that the shaft 18 may freely rotate with respect to the sectional linked connection between said shaft and the lever 33. Upon the lower end of this lever 33 a roller 41 is mounted and is positioned in the cam track 30 between the periphery of the disk 24 and the rail 26.

To the lower end of the bracket 32 one end of a lever 42 is pivotally connected as at 43. This lever is disposed horizontally and is provided intermediate of its ends with a roller 44 which is disposed in the other cam track 31 between the cam disk 25 and the rail 27. To the other end of the lever 42 the lower end of a rod 45 is pivotally connected. A collar 46 is clamped or otherwise securely fixed on the shaft 18 between the bearings 19 and the upper end of the rod 45 is connected to this collar by means of the universal ball and socket connection 47.

In the operation of the apparatus as above described it will be understood that an intermittent movement is imparted to the sprocket chains 10 to successively dispose the skein

holders carried by said chains at the upper sides of the sprockets and the cam mechanism for actuating the flier 20 is operated in timed relation to this intermittent actuation of the carrier chains for the skein holders. This automatic control mechanism whereby the operation of the flier and of the carrier for the skein holders is properly timed or synchronized forms the subject matter of my copending application, Serial No. 346,836, filed December 3, 1919.

During one complete cycle of movements the winding mechanism winds upon the skein holder a skein comprising a main or primary loop and a plurality of intermediate or subsidiary loops. The main or primary loop is the loop which passes completely around the skein holder. The subsidiary or intermediate loops are those that are formed within the main or primary loop. The main or primary loop is first partially formed, the intermediate or subsidiary loops are then wound, and the main or primary loop is then completed. The movements of the flier arm 20 in winding the thread upon the holder is clearly shown diagrammatically in Fig. 5. At the beginning of the winding operation the rollers 41 and 44 are disposed in their respective cam paths as shown in Fig. 4. In the initial movement of the flier arm 20 the thread is carried transversely of the skein holder between the bifurcated arms 14 to form one side of the main or primary loop. This movement is effected through the medium of the lever 33 which is actuated by the cam 24. In this movement of the lever, the shaft 18 is shifted axially through the medium of the link 36. In the next operation, as shown in Fig. 5, the end of the flier carrying the thread is moved longitudinally of the skein holder to engage the thread in the bifurcated end of the holder arm 15 and thereby form a second side of the main or primary loop. As this arm is disposed intermediate of the plane of the arms 14, it is obvious that in order to secure a tightly wound skein, the flier arm must also be moved transversely of the skein holder during such longitudinal movement. This operation is effected by the simultaneous action of the cams 24 and 25 upon the rollers 41 and 44. The cam 25 together with its cam rail acting on the roller 44 actuates the lever 42 and through the medium of the rod 45, the shaft 18 is rocked or rotated in its bearings at the same time that it is being axially moved by the lever 33. This same composite movement of the flier is repeated alternately in opposite directions longitudinally of the skein holder as clearly indicated in the diagram of Fig. 5 so as to form two subsidiary or intermediate loops in the yarn or thread which are within the circuit of the main or primary loop superposed upon each other and extend in convergent 180

relation from the spaced arms 14' of the holder to the extremity of the arm 15. Finally the thread is carried back to the starting point in the actuation of the cams so that the main or primary skein loop is closed and the cycle of winding operations completed. In this manner the skein may be very rapidly wound and by looping the yarn or thread as seen in Fig. 5, I produce 10 a skein in the form of a plurality of multi-strand superposed loops. These loops may be readily separated when the yarn or thread is to be used without entanglement of the strands with each other. Thus it will be 15 apparent that with the use of a skein holder of relatively short length, by means of the improved mechanism, the thread is wound in such manner as to provide a completed skein of maximum length. When one skein 20 has thus been wound, the carrier chains 10 are automatically actuated to position the next skein holder at the upper sides of the sprockets 8. In this movement of the carrier, the thread is drawn through the eyes 25 on the flier arm 20 as the holder carrying the completed skein moves below the end of the flier arm. I also contemplate, in the completed machine, providing an automatic mechanism for cutting the strand of thread 30 extending between the skein holders, but as this mechanism likewise forms no part of the present invention, it is not herein illustrated or described.

From the foregoing description considered 35 in connection with the accompanying drawings, the construction, manner of operation and several advantages of my invention will be clearly and fully understood. I have found in practice that the winding mechanism may be operated at very high speed to accurately wind the skeins in the manner above explained. I have herein referred 40 to the sprockets 8 and the chains 10 as constituting the means whereby the skein holders are successively positioned to receive the skein windings. It is, however, to be understood that if desired, other carrier means for the skein holders may be substituted in lieu 45 of the chains and sprockets. Likewise, in so far as the subject matter of the present application is concerned skein holders of other form and construction than that referred to may be employed. However, the holder 50 which I have herein shown permits the skein 55 to be rapidly removed by the use of a suitable trip to engage arm 17 of the movable holder member simultaneously with the release of the latch 16. When this holder member 13 is swung or moved to a position 60 at right angles to the fixed member 12, the skein loops may be readily disengaged from the bifurcated arms of the holder members.

The cam construction and arrangement 65 together with the operating connections between these cams and the rotary and axially

movable shaft provides a very simple and compact arrangement of parts, which are positive and reliable in action and not likely to easily get out of order. It will also be appreciated that in view of the very simple 70 form of the mechanism which I have devised, the invention may be produced at comparatively small manufacturing cost.

While I have herein shown and described one practical embodiment of my invention 75 which has given highly satisfactory results in actual use, it is nevertheless to be understood that the apparatus may also be exemplified in numerous other alternative constructions. Accordingly, therefore, I reserve the privilege of resorting to all such legitimate changes in the form, construction and relative arrangement of the several parts as may be fairly embodied within the spirit and scope of the invention as claimed. 80

I claim:

1. In a skein winding mechanism, a thread carrier, rotatable and axially movable means for supporting the thread carrier, and means for simultaneously rotating the carrier supporting means, and moving it axially to impart movement to the thread carrier in two directions at right angles to each other. 90

2. In a skein winding mechanism, a rotatable and axially movable shaft, a thread carrier fixed to said shaft, and means operating to simultaneously rotate and axially move said shaft and thereby impart a movement to the carrier in two directions. 95

3. In a skein winding mechanism, a thread holder having a plurality of thread supports, a thread carrier, means for supporting the thread carrier, means for imparting movement to the carrier to cause it to wind a series of primary loops about all the thread 100 supports and a plurality of series of subsidiary loops about some of the thread supports. 105

4. In a skein winding mechanism, a thread carrier, means for supporting the thread 110 carrier, and means for imparting movement to the thread carrier to cause it to wind a primary loop and a plurality of subsidiary loops within the circuit of the primary loop.

5. In a skein winding mechanism, a rotatable and axially movable shaft, a thread carrier fixed to said shaft, and cam actuated means for operating said shaft to move the carrier in two directions. 115

6. In a skein winding mechanism, a rotatable and axially movable shaft, a thread carrier fixed to said shaft, a member connected to said shaft to move the same axially, a member to rotate said shaft, and cam means for actuating said members. 120

7. In a skein winding mechanism, a rotatable and axially movable shaft, a thread carrier fixed to said shaft, a member connected to said shaft to move the same axially, a member to rotate said shaft, and sep- 130

arate cams for actuating the respective members to impart a combined axial and rotary movement to the shaft.

8. In a skein winding mechanism, a rotatable and axially movable shaft, a thread carrier fixed to said shaft, a member connected to said shaft to move the same axially, a member to rotate said shaft, and relatively fixed rotary cams for actuating the respective members to impart a combined axial and rotary movement to said shaft.
9. In a skein winding mechanism, a rotatable and axially movable shaft, a thread carrier fixed to said shaft, a lever, a universal connection between one end of said lever and said shaft, a cam co-acting with the lever to shift said shaft axially, and concurrently actuated means operatively connected to said shaft to rotate the shaft during its axial movement.

10. In a skein winding mechanism, a rotatable and axially movable shaft, a thread carrier fixed to said shaft, a lever, a universal connection between one end of said lever and the shaft, means for actuating said lever to move the shaft axially, a second lever, a rod connected at one of its ends to the latter lever and its other end to the shaft, and additional means to actuate the latter lever and thereby rotate the shaft during its axial movement.

11. In a skein winding mechanism, a rotatable and axially movable shaft, a thread carrier fixed to said shaft, a lever operatively connected at one of its ends to said shaft, a cam co-acting with the other end of said lever to actuate the same and move the shaft

axially, a second cam, and means operatively connected to the shaft and actuated by said second cam to rotate the shaft during its axial movement.

12. In a skein winding mechanism, a rotatable and axially movable shaft, a thread carrier fixed to said shaft, a lever, means operatively connecting said lever at one end to the shaft, means co-acting with the other end of said lever to actuate the same and axially move the shaft, a second lever pivotally mounted at one end, a rod operatively connected to the other end of said lever, a bracket fixed to the shaft, a universal connection between said bracket and the other end of the rod, and means for actuating the latter lever to thereby rotate the shaft during its axial movement.

13. In a skein winding mechanism, a rotatable and axially movable shaft, a thread carrier fixed to said shaft, a lever fulcrumed intermediate of its ends, means operatively connecting one end of said lever to the shaft, a cam co-acting with the other end of said lever to actuate the same and impart an axial movement to the shaft, a second cam having a fixed relation to the first named cam, a second lever pivotally mounted at one of its ends and actuated by said second named cam, and means operatively connecting the other end of the second named lever to said shaft to thereby impart a rotary movement to the shaft during its axial movement.

In testimony that I claim the foregoing as my invention, I have signed my name.

MAX OTTO CLAUSS.
